FRANK M. SLOUGH, OF ELYRIA, OHIO, ASSIGNOR TO THE ELYRIA ENAMELED PRODUCTS COMPANY, OF ELYRIA, OHIO, A CORPORATION OF OHIO.

LIQUID-AGITATING MECHANISM.

1,420,767.

Specification of Letters Patent. Patented June 27, 1922.

Application filed July 1, 1920. Serial No. 393,429.

To all whom it may concern:

Be it known that I, FRANK M. SLOUGH, a citizen of the United States, residing at Elyria, in the county of Lorain and State 5 of Ohio, have invented certain new and useful Improvements in Liquid-Agitating Mechanisms, of which the following is a full, clear, concise, and exact description, such as will enable others skilled in the art to which 10 it appertains to make and use the same.

My invention relates to liquid agitating mechanisms, and particularly to such mechanisms wherein liquid contained in a tank is moved in diverse directions therein, under 15 the influence of one or more propellers suitably rotated by a source of power.

It is an object of my invention to produce such a device as may be simply and cheaply constructed and will operate most efficiently, 20 and in which mechanism the sanitary conditions, when the device is used for processing food products, are maintained to a high standard.

It has heretofore been proposed to place 25 more than a single rotatable propeller in a mixing tank substantially of the form herein contemplated, but such efforts have, so far as I am aware, been more or less unsuccessful, because either the second propeller 30 neutralizes to a large degree the effect of the first propeller, or merely passes along currents set in motion by the other propeller and only slightly adds to the velocity of such currents.

In my present invention, I am enabled to 35 use a plurality of propellers, herein illustrated as two propellers, which co-act in a new and novel way to produce a maximum of liquid agitation, and each propeller at the 40 same time causing currents which deflect the currents produced by the other propeller without detracting from their velocity or ability to perform the function of mixing.

Other objects of my invention and the 45 invention itself will be better understood by referring to the drawings accompanying this specification.

Figure 1 of the drawings shows an embodiment of my invention in vertical cross 50 section.

Figure 2 shows a plan view of said embodiment, the view of Figure 1 being taken on a line I—I of Figure 2.

Referring now to the drawings, at A—A

are shown the curved side walls of a tank, 55 herein illustrated as cylindrical, and at B is shown a downwardly inclined bottom wall thereof, the side walls and bottom wall being joined at C.

An opening for the egress of liquid from 60 the tank is illustrated at D, and the tank is shown as being jacketed, having a jacket E, whereby the contents of the tank may be heated or cooled by the inclusion of a heating or cooling medium within the jacket. 65 An opening F is provided in the said jacket for the ingress of the heating or cooling medium, and an opening G is provided for the egress thereof.

Passing through a side wall of the tank, 70 at points H and J, are a plurality of propeller shafts, herein illustrated as being two in number, said shafts being shown at K and L.

On the ends of the said shafts, inside the 75 tank, are mounted a pair of propellers N and O and on the opposite ends thereof, outside the tank, are shown pulleys P and P', whereby power from a motor may be caused to rotate the said propeller shafts carrying 80 the said propellers.

The propeller shafts are herein illustrated as being mounted substantially in the same horizontal plane and substantially parallel to each other and to the axis of the tank, 85 each preferably being equidistant from the plane of the said axis; but it is obvious that these precise relations may be departed from somewhat, and still realize the mode of operation, and the results secured thereby, by 90 the use of this invention.

The propellers are preferably pitched and rotated in such a direction as will produce the same thrust tendency upon liquid in its vicinity, that is, they may be both left-handed propellers, both operating counterclockwise, or one of them may be a left-handed propeller and the other a right-handed propeller, but rotating in opposite directions; I contemplate both arrangements and directions of rotation.

By this arrangement portions of the liquid contents of the tank may pass from the propellers in parallel paths, reacting, however, on each other so as to cause deflection from 105 the said paths; portions of the said currents striking the side walls of the said tank and are caused to be deflected thereby, setting up

resultant deflected currents which pass in various directions over the entire body of the liquid.

I am aware that it has been previously proposed to place a propeller in a cylindrical tank, the shaft of the said propeller being in a horizontal plane, and in a vertical plane not co-inciding with an axis of the tank, but being parallel thereto; but such a device is found to be unsuccessful because of the fact that currents are caused to be propelled around and around the central vertical axis of the tank producing what is known in the art as a "merry-go-round" effect, which is not conducive to the thorough intermingling of the various particles of the liquid contents of the tank, nor to their uniform exposure to the thermal effects of the side and bottom walls of the tank as herein contemplated.

Having thus described my invention, I am aware that numerous and extensive departures may be made from the embodiment herein illustrated and described, but without departing from the spirit and scope of my invention. My invention is defined in the following claims:

1. In combination, a tank, a propeller, a propeller shaft, said propeller being adapted to be rotated by the said shaft, cylindrical side walls for the said tank, said propeller being adapted to be rotated in a vertical plane located parallel to but on one side of a tank diameter, the axis of rotation being in a vertical plane not corresponding to a tank diameter, but parallel thereto, the bottom of the tank being inclined to the plane to the attaching edge of the side walls.

2. In combination, a tank, a pair of propellers, a pair of propeller shafts, the said propellers being mounted one on each shaft, said propeller shafts passing both through the same semi-circular portion of the tank wall, and said propellers being both located on the same side of the tank.

3. In combination, a tank, a pair of propellers, a pair of propeller shafts, the said propellers being mounted one on each shaft, said propeller shafts passing both through the same semi-circular portion of the tank wall, and each of the said propeller shafts being parallel to the other.

4. In combination, a tank, a pair of propellers, a pair of propeller shafts, the said propellers being mounted one on each shaft, said propeller shafts passing both through the same semi-circular portion of the tank wall, said propellers being both located on the same side of the tank, and each of the said propeller shafts being parallel to the other.

5. In combination, a tank, a pair of propellers, a pair of propeller shafts, the said propellers being mounted one on each shaft, said propeller shafts passing both through

the same semi-circular portion of the tank wall, said propellers being both located on the same side of the tank, and said propellers both being adapted to rotate in substantially the same vertical plane.

6. In combination, a tank, a pair of propellers, a pair of propeller shafts, the said propellers being mounted one on each shaft, said propeller shafts passing both through the same semi-circular portion of the tank wall, said propellers being both located on the same side of the tank, and each of the said propellers being reversely pitched with respect to the other.

7. In combination, a tank, a pair of propellers, a pair of propeller shafts, the said propellers being mounted one on each shaft, said propeller shafts passing both through the same semi-circular portion of the tank wall, said propellers being both located on the same side of the tank, each of the said propellers being reversely pitched with respect to the other, and adapted to be rotated in the same direction.

8. In combination, a tank, a pair of propellers, a pair of propeller shafts, the said propellers being mounted one on each shaft, said propeller shafts passing both through the same semi-circular portion of the tank wall, said propellers being both located on the same side of the tank, and said propeller shafts being located substantially in the same horizontal plane.

9. In combination, a tank, a pair of propellers, a pair of propeller shafts, the said propellers being mounted one on each shaft, said propeller shafts passing both through the same semi-circular portion of the tank wall, each of the said propeller shafts being parallel to the other, and said propellers both being adapted to rotate in substantially the same vertical plane.

10. In combination, a tank, a pair of propellers, a pair of propeller shafts, the said propellers being mounted one on each shaft, said propeller shafts passing both through the same semi-circular portion of the tank wall, each of the said propeller shafts being parallel to the other, and each of the said propellers being reversely pitched with respect to the other.

11. In combination, a tank, a pair of propellers, a pair of propeller shafts, the said propellers being mounted one on each shaft, said propeller shafts passing both through the same semi-circular portion of the tank wall, each of the said propeller shafts being parallel to the other, and adapted to be rotated in the same direction.

12. In combination, a tank, a pair of propellers, a pair of propeller shafts, the said propellers being mounted one on each shaft, said propeller shafts passing both through the same semi-circular portion of the tank wall, each of the said propeller shafts being

parallel to the other, and said propeller shafts being located substantially in the same horizontal plane.

13. In combination, a tank, a propeller, a propeller shaft, said propeller being adapted to be rotated by the said shaft, cylindrical side walls for the said tank, said propeller being adapted to be rotated in a vertical plane located parallel to but one side of a

tank diameter, the axis of rotation being in 10 a vertical plane not corresponding to a tank diameter, but parallel thereto, the bottom of the tank being inclined to the plane to the attaching edge of the side walls.

In witness whereof, I have hereunto 15 signed my name this 26th day of June, 1920.

FRANK M. SLOUGH.
